[57] CLAIM

The ornamental design for a music box or the like, as shown and described.

DESCRIPTION

FIG. 1 is a top front perspective view of a music box or the like showing my new design;

FIG. 2 is a left side elevational view thereof; the opposite side being a mirror image of the side shown;

FIG. 3 is a rear elevational view thereof;

FIG. 4 is a top plan view thereof; and

FIG. 5 is a bottom plan view thereof.

The broken lines representing the light bulb are shown for illustrative purposes only and forms no part of the claimed design.
